UNITED STATES PATENT OFFICE.

ARTHUR WHITE, OF SHEBOYGAN FALLS, WISCONSIN.

WHEELED TOY.

1,362,769.

Specification of Letters Patent. Patented Dec. 21, 1920.

Application filed October 11, 1917. Serial No. 195,992.

To all whom it may concern:

Be it known that I, ARTHUR WHITE, a citizen of the United States, and resident of Sheboygan Falls, in the county of Sheboygan and State of Wisconsin, have invented new and useful Improvements in Wheeled Toys, of which the following is a description, reference being had to the accompanying drawings, which are a part of this specification.

The invention relates to improvements in wheeled toys.

It is one of the objects of the present invention to provide a wheeled toy which may be formed almost wholly of wood, and in which the parts are assembled in a simple manner to form a strong, simple and inexpensive toy for children.

A further object of the invention is to provide a wheeled toy of the tricycle type upon which a child may sit and propel by pushing on the walk with the feet.

A further object of the invention is to provide a wheeled toy in which the parts are assembled in a manner to reinforce each other part.

With the above and other objects in view the invention consists of the improved wheeled toy and its parts and combinations as set forth in the claims and all equivalents thereof.

In the accompanying drawings in which the same reference characters indicate the same parts in all of the views:

Figure 1 is a side view of the improved wheeled toy, portions broken away and in section to show interior construction;

Fig. 2 is an inverted plan view;

Fig. 3 is a rear end view;

Fig. 4 is a detail sectional view of the steering head and adjacent parts;

Fig. 5 is a top view of a modified form of steering handle; and

Fig. 6 is a sectional view thereof taken on line 6—6 of Fig. 5.

Referring to the drawings the numeral 8 indicates the seat board of the improved toy which extends horizontally and is formed with a narrow forwardly extending neck portion 9 which connects to and forms part of the steering head 10 of the vehicle. Reinforcing blocks 11 secured to the forward end portion of the neck, above and below the neck, and a cap member 12 connected to the blocks 11 by screws 13 form the steering head or bearing of the frame portion 8. The

head is provided with an obliquely extending opening 14 to receive the steering shank 15 of the forks 16. The shank is held against vertical movement by the upper angular ends 17 of the forks 16 and a pin 18 extending transversely through the fork shank above the steering head. Washers 19 are mounted on the shank between the head and the transverse pin and the angular ends 65 of the forks to form better bearing surfaces.

The shank 15 is preferably formed of wood and at its lower end portion the forks 16 formed of metal are connected on the opposite sides of the shank by rivets or bolts 70 20. The upper end of the shank is reduced in diameter to receive the steering wheel handle 21 and to form an annular shoulder 22 against which the hub of the steering wheel handle bears. Nails or other securing means 23 extend through the hub and into the shouldered portion of the shank, and a screw 24 extending through a cap washer 25 and into the reduced portion of the shank firmly secures the steering wheel 80 handle to the shank. A front steering and supporting wheel 26 is interposed between the lower end portion of the forks and is journaled on an axle 27 extending through the forks and riveted over on its ends. 85

A transversely extending reinforcing bar 28 fastened to the under side of the seat board 8 has connected to the rear side thereof the upper rabbeted ends 29 of the crossed or diagonally extending supporting bars 30, 90 the lower rabbeted ends 31 of which are connected to the rear side of the bolster bar 32. Horizontally extending bolts 33 connect the upper ends of the crossed supporting bars 30 to the bar 28 and similar bolts 34 95 connect the lower ends of the crossed bars to the bolster bar 32. The rabbeted end portions of the crossed supporting bars 30 form shoulders 35 which bear upon the respective bars connected to the crossed bars and thus 100 form a rigid connection therebetween. The medial adjacent portions 36 of the crossed bars are also rabbeted to form a flush reinforcing connection therebetween.

Reach bars 37 connected to the forward 105 end portion of the necks 9 and to the upper block 11 by bolts 38 extend divergently rearwardly and downwardly and engage the front side of the bolster 32. The rear ends of the reach bars are securely fastened to 110 the bolster by angular metal reinforcing members 39, the forward ends 40 of which

extend parallel to the reach bars and are connected thereto by rivets 41. Portions 42 of the reinforcing members 39 extend outwardly from the forward ends and parallel 5 to the bolster bar 32 and axle portions 43 extend rearwardly over the opposite ends of the bolster bar to receive the screw axles 44. Said screw axles extend through the axle portions of the members and are threaded 10 into the ends of the bolster bar and have supporting wheels 45 journaled thereon. Washers 46 mounted on the axle screws are interposed between the wheels and the heads of the screws. The bolts 34 also extend 15 through the outwardly bent portions 42 of the reinforcing members 39 to securely fasten the members to the bolster.

In the modified form shown in Figs. 5 and 6 a handle bar 47 is substituted for the 20 wheel and is fastened to the steering stem by forming a transversely extending groove 48 in the upper end of the stem for receiving a medial squared portion 49 of the handle bar and placing a U-shaped metal strap 25 50 over the bar and the grooved portion of the stem and riveting said strap to the stem by rivets 51.

From the foregoing description it will be 30 seen that the toy may be inexpensively manufactured almost entirely from wood and that a very strong durable structure is produced due to the triangular arrangement and connection of the parts.

What I claim as my invention is:

1. A wheeled toy, comprising a frame of 35 triangular form having a two part steering head portion and a transversely extending reinforcing bar portion and a bolster, said frame being formed in part of crossed 40 diagonally extending bars connected at their upper ends to the reinforcing bar and at their lower ends to the bolster bar, a forked member extending vertically through and journaled in the steering head portion and having a steering means at its upper end and a wheel at its lower end, and supporting 45 wheels carried by the bolster bar.

2. A wheeled toy, comprising a frame of 50 triangular form longitudinally and having a two part steering head portion and a bolster bar and a transversely extending reinforcing bar, said frame being formed in part of connected-together crossed diagonally extending bars connected at their upper ends 55 to the reinforcing bar and at their lower ends to the bolster bar, a forked member extending through and journaled in steering head portion and having a steering means at its upper end and a wheel at its lower end, axle members projecting from the bolster, and supporting wheels journaled on the axle members.

3. A wheeled toy, comprising a seat having 60 a forwardly extending neck portion, a two part steering head forming part of the for-

ward end portion of said neck, a forked member journaled in the steering head and having a steering means at its upper end and a wheel at its lower end, a transversely extending reinforcing bar mounted beneath the 70 rear lower side portion of the seat, connected together crossed diagonally extending supporting bars connected at their upper ends to the reinforcing bar, a bolster bar connected to the lower end portions of the supporting bars, axle members projecting outwardly from the bolster, a pair of reach bars connected to the neck portion and the bolster, and supporting wheels journaled on the 75 axles.

4. A wheeled toy, comprising a frame of triangular form longitudinally and having a seat portion and a two part steering head portion and a bolster portion, said frame being formed in part of connected together 80 crossed diagonally extending bars, and diagonally extending reach bars which connect the bolster portion to the head portion, a transversely extending reinforcing bar mounted beneath the rear lower side 85 part of the seat portion and connected to the upper ends of the diagonally extending bars, the lower ends of the diagonally extending bars being connected to the bolster, a forked member having a steering means at its upper end and a wheel at its lower end, axle members projecting outwardly from the bolster member, and supporting wheels journaled by the axles.

5. A wheeled toy, comprising a seat member having a forwardly projecting neck portion, a two part steering head formed on the front end of the neck portion, a forked member journaled between the two parts of the steering head and having a steering means 100 at its upper end and a wheel at its lower end, a transversely extending reinforcing bar positioned beneath and connected to the rear portion of the seat member, a bolster bar positioned below the reinforcing bar 105 and having outwardly extending axle portions, crossed diagonally extending bars connecting the bolster bar to the reinforcing bar, reach bars connecting the bolster bar to the steering head, and supporting wheels 110 journaled on the axle portions of the bolster.

6. A wheeled toy, comprising a seat member having a forwardly projecting neck portion, a two part steering head formed on the front end of the neck portion, a forked member journaled between the two parts of the steering head and having a steering means at its upper end and a wheel at its lower end, a transversely extending reinforcing bar positioned beneath and connected to the rear 115 portion of the seat member, a bolster bar positioned below the reinforcing bar and having outwardly extending axle portions, crossed diagonally extending bars connecting the bolster bar to the reinforcing bar, 120

125

130

reach bars connected to the steering head and extending rearwardly divergently toward the opposite end portions of the bolster and connected thereto, and supporting 5 wheels journaled on the axle portions of the bolster.

7. A wheeled toy, comprising a seat member having a forwardly projecting neck portion, a steering head formed on the front 10 end of the neck portion, a forked member journaled in the steering head and having a steering means at its upper end and a wheel at its lower end, a transversely extending reinforcing bar positioned beneath and connected to the seat member, a bolster bar positioned below the reinforcing bar, crossed diagonally extending bars connecting the bolster bar to the reinforcing bar, reach bars connected to the steering head and extending 15 divergently toward the opposite end portions of the bolster, metal reinforcing members connecting the rear ends of the reach bars to the bolster and extending around the 20 ends of said bolster, axles carried by said bolster and projecting outwardly through the metal reinforcing members, and supporting 25 wheels journaled on the axles.

8. A wheeled toy, comprising a seat member having a forwardly projecting neck portion, a steering head formed on the front 30 end of the neck portion, a forked member journaled in the steering head and having a steering means at its upper end and a wheel at its lower end, a transversely extending reinforcing bar positioned beneath and connected to the seat member, a bolster bar positioned below the reinforcing bar, crossed 35 diagonally extending bars connecting the bolster bar to the reinforcing bar, the upper 40 and lower ends of said crossed bars having rabbeted portions which engage the bolster and the transverse reinforcing bar, the crossed portions of said crossed bars also being rabbeted together, reach bars connected 45 to the steering head and extending divergently toward the opposite end portions of the bolster, metal reinforcing members connecting the rear ends of the reach bars to the bolster and extending around the ends of 50 said bolster, screw axles extending through the metal members and threaded into the

bolster, and supporting wheels journaled on the screw axles.

9. A wheeled toy, comprising a two-part seat member having a forwardly projecting 55 neck portion, a steering head formed on the front end of the neck portion, a forked member journaled in the steering head and having a steering means at its upper end and a wheel at its lower end, a transversely extending 60 reinforcing bar positioned beneath and connected to the seat member, a bolster bar positioned below the reinforcing bar, crossed diagonally extending bars connecting the bolster bar to the reinforcing bar, the 65 upper and lower ends of said crossed bars having rabbeted portions which engage the bolster and the transverse reinforcing bar, the crossed portions of said crossed bars also being rabbeted together, reach bars 70 connected to the steering head and extending divergently toward the opposite end portions of the bolster, metal reinforcing members connecting the rear ends of the reach bars to the bolster and extending around 75 the ends of said bolster, bolts extending through the crossed bars and the bolster and the metal reinforcing members, screw axles extending through the metal members and threaded into the bolster, and supporting 80 wheels journaled on the screw axles.

10. A wheeled toy in part, comprising a steering head portion, and a steering fork shank journaled in the steering head, the fork portion of said steering fork being 85 formed of two metal strips which are fastened on opposite sides of the shank and have their upper ends bent outwardly to form supporting shoulders for the steering head.

11. A wheeled toy in part, comprising a steering head portion, and a steering fork shank journaled in the steering head, the fork portion of said steering fork being 95 formed of two metal strips which extend alongside of and are fastened on opposite sides of the shank and have their upper ends bent outwardly at an angle to form supporting shoulders for the steering head.

In testimony whereof I affix my signature. 100

ARTHUR WHITE.
